UNITED STATES PATENT OFFICE.

MABEL H. SLATER, OF WEBSTER, MASSACHUSETTS.

REFRIGERATOR.

1,089,016.

Specification of Letters Patent. Patented Mar. 3, 1914.

Application filed September 25, 1913. Serial No. 791,783.

To all whom it may concern:

Be it known that I, MABEL H. SLATER, a citizen of the United States, residing at Webster, in the county of Worcester and State of Massachusetts, have invented new and useful Improvements in Refrigerators, of which the following is a specification.

This invention relates to an improved refrigerator, the object of the invention being to provide a refrigerator in which the ice receptacle is movable within the casing of the refrigerator and is connected by suitable means or mechanism to an indicator whereby the amount of ice in the refrigerator is indicated by said indicator, the indicator being placed upon the outside of the casing in a convenient position, so that at a glance the amount of ice in the refrigerator can be noted, and also when a new supply of ice is being placed in a refrigerator the weight of the same will be shown by the index finger of the indicator.

The invention consists in a refrigerator having a movable ice receptacle contained therein in combination with an indicator and mechanism whereby said indicator will be operated to show the different positions occupied by said ice receptacle and consequently the amount of ice contained in said ice receptacle.

The invention further consists in the combination and arrangement of parts set forth in the following specification and particularly pointed out in the claims.

Referring to the drawings: Figure 1 is a sectional elevation of my improved refrigerator taken on line 1—1 of Fig. 2; Fig. 2 is a sectional elevation taken on line 2—2 of Fig. 1. Fig. 3 is a front elevation of a portion of a refrigerator, with the indicator and a portion of the connecting mechanism thereon. Fig. 4 is a plan view of the refrigerator.

Like numerals refer to like parts throughout the several views of the drawings.

In the drawings, 5 is the casing of the refrigerator, 6 is the movable ice receptacle, 6' is a stationary receptacle into which the water from the melted ice drips, 7 and 8 are receptacles for food, 9 is the outlet pipe from the refrigerator, 10 is the overflow pipe in the receptacle 6' and 11 is the outlet pipe from said receptacle 6'.

12 is a valve connected to the outlet pipe 11, whereby ice water may be withdrawn from the receptacle 6'.

The ice 13 rests upon a suitable grating 14. Flexible members 15 are fastened at one end thereof, as at 16, to two of the corners at one side of the receptacle 6. Said flexible members 15 extend over pulleys 17 rotatably mounted on brackets 18 fast to the top of the casing 5. The other ends of said flexible members 15 pass over and are fastened to pulleys 19 which are fastened to a shaft 20 rotatably mounted in bearings 21 fast to the casing 5.

Flexible members 22 are fastened to the receptacle 6, as at 23, at the corners of said receptacle located on the side thereof opposite that to which the members 15 are attached. Said flexible members 22 extend upwardly through the top of the casing 5 and over pulleys 24 rotatably mounted upon brackets 25 fast to the top of said casing. Said flexible members 22 extend to the under side of the pulleys 19 and, extending partly around said pulleys, are fastened thereto. Thus it will be seen that the weight of the ice receptacle 6 and the ice 13 contained therein act to rotate the shaft 20 counter-clockwise, as viewed from the front of the refrigerator.

The shaft 20 has a gear 26 fast thereto which meshes into a pinion 27 rotatably mounted on the indicator casing 28 and having an index finger 29 fast thereto so that when the shaft 20 is rotated counter-clockwise the indicator will be rotated in the opposite direction or clockwise and the finger 29 will be moved to different positions around the dial 30 of said indicator. The dial 30 is sub-divided and provided with numerals indicating the number of pounds of ice contained within the ice receptacle.

A spring 31 encircles the shaft 20 and is fastened at one end thereof to a collar 32 which is fastened to the shaft 20 by means of a set-screw 33. The opposite end of said spring is fastened to a bracket 34 which is fast to the top of the casing 5. An arm 35 is fastened to the shaft 20 and engages at its free end a stop-screw 36 which has screw-threaded engagement with a bracket 37 fast to the top of the casing.

The general operation of the device hereinbefore described is as follows: The ice 13 is placed in the receptacle 6. The spring 31 is so adjusted that when the receptacle 6 is empty the index finger 29 will point to zero on the dial 30. When the ice 13 is placed within said receptacle 6 upon the grating

14, the receptacle will move downwardly and the flexible members 15 and 22 attached to said receptacle will rotate the shaft 20 counter-clockwise against the action of the 5 spring 31, moving the arm 35 away from the set-screw 36 and rotating the index finger clockwise to a point on the dial corresponding with the weight of the ice placed in said receptacle, the dial thus indicating the 10 weight of the ice in the receptacle. As the ice melts the water will drip into the stationary receptacle 6' and either overflow through the overflow pipe 10 and pass down through the refrigerator, outside the food 15 receptacles 7 and 8, and out of the refrigerator through the outlet pipe 9, or it may be withdrawn from the receptacle 6' through the pipe 11 by means of the outlet valve 12. As the ice melts, the weight becoming less, 20 the spring 31 will act to move the receptacle 6 with the ice 13, upwardly in the refrigerator and rotate the shaft 20 clockwise, thus rotating the index finger counter-clockwise so that said index finger will gradually 25 return to zero, whereupon all of the ice will have been melted and the arm 35 will rest against the set-screw 36. By rotating the collar 32 to different positions upon the shaft 20 the tension upon the spring 31 may be 30 regulated at will and said collar set in position on said shaft, after such regulation, by the set-screw 33.

It is evident that the valve 12 may be used when it is desired to obtain ice water for 35 drinking purposes or to empty the ice chest of water and prevent any danger of overflow on the floor during the night.

Having thus described my invention, what I claim and desire by Letters Patent to secure is:

40 1. A refrigerator having, in combination, a casing, a receptacle for ice located within said casing and movable vertically therein, an indicator, a rotary shaft adapted to operate said indicator, a plurality of flexible members connecting said shaft to said receptacle whereby said shaft may be rotated in one direction, and means adapted to oppose the rotation of said shaft in said direction and adapted to rotate said shaft in the opposite direction.

45 2. A refrigerator having, in combination, a casing, a receptacle for ice located within said casing and movable vertically therein,

an indicator, a rotary shaft adapted to operate said indicator, a plurality of flexible members connecting said shaft to said receptacle and a torsional spring encircling said shaft, one end fast thereto and the other end fast to a stationary member whereby the rotation of said shaft is opposed in one direction and assisted in the opposite direction.

55 3. A refrigerator having, in combination, a casing, a receptacle for ice located within said casing and movable vertically therein, an indicator, a rotary shaft adapted to operate said indicator, a plurality of flexible members connected at one end thereof to said receptacle, a shaft rotatably mounted 60 on the top of said casing, guide pulleys intermediate said shaft and receptacle, over which pulleys said flexible members pass, the other ends of said flexible members connected to said shaft and adapted to rotate 65 the same in one direction, means adapted to rotate said shaft in the opposite direction and an indicator adapted to be operated by the rotation of said shaft whereby movements of said ice receptacle will be registered by said indicator.

70 4. A refrigerator having, in combination, a casing, a receptacle for ice located within said casing and movable vertically therein, an indicator, a rotary shaft adapted to operate said indicator, a plurality of flexible members connected at one end thereof to said receptacle, a shaft rotatably mounted 75 on the top of said casing, guide pulleys intermediate said shaft and receptacle, over which pulleys said flexible members pass, pulleys fast to said shaft to which the other ends of said flexible members are connected and adapted to rotate said shaft in one direction, a spring connected to said shaft and 80 adapted to rotate the same in the opposite direction, an indicator embodying an index finger and gearing connecting said index finger to said shaft whereby movements of 85 said ice receptacle cause said index finger 90 to assume different positions.

95 In testimony whereof I have hereunto set my hand in presence of two subscribing witnesses.

MABEL H. SLATER.
